TUBE HOLDER FOR TOOTHBRUSH

Arthur J. Gygie, 16316 S. Wilton Place, Gardena, Calif.

Filed Dec. 28, 1961, Ser. No. 68,101

Term of patent 7 years

(Cl. D4—3)

FIGURE 1 is a perspective view of a tube holder for toothbrush showing my new design as seen from the front, with the cap raised;

FIGURE 2 is a side elevational view with the cap closed;

FIGURE 3 is a rear elevational view of the same;

FIGURE 4 is a top plan view with the cap closed;

FIGURE 5 is a bottom plan view of the same; and

FIGURE 6 is a top plan view with the cap raised.

I claim:

The ornamental design for a tube holder for toothbrush, substantially as shown.
